UNITED STATES PATENT OFFICE

2,563,297

ELECTRICAL PRECIPITATOR, INCLUDING
AN ELECTRODE WASHING DEVICEJohn Herbert Wilson, Middlesex, N. J., assignor
to Research Corporation, New York, N. Y., a
corporation of New York

Application November 24, 1947, Serial No. 787,840

9 Claims. (Cl. 183—7)

1

This invention relates to electrical precipitators and more particularly to an electrical precipitator including a device for washing or wetting the electrodes thereof.

An object of the invention is to provide a washing device for the electrodes of electrical precipitators wherein wide distribution of washing liquid is obtained with a minimum number of nozzles.

Another object is to provide a washing device of the type described having relatively fixed nozzles that distribute jets of washing liquid over electrode areas several times greater than the cross sectional area of the jets.

Still another object is to provide in an electrical precipitator, including complementary high tension and extended surface electrodes, an extended surface electrode washing device positioned entirely outside the regions of strong electric field, whereby to avoid distortion of the field with attendant decrease in precipitator efficiency and danger of short circuiting.

A further object is to provide an electrode washing device of this character that is relatively simple to construct and install, that is easy to operate and maintain, and that is rugged and has a long service life, thus contributing to economy in manufacture and operation.

The foregoing and other objects of the invention are realized in an electrical precipitation apparatus having complementary high tension and extended surface electrodes and equipped with an extended surface electrode washing device including a nozzle positioned to direct a jet of washing liquid against the extended surface electrode, conduit means supplying washing liquid to the nozzle, and means for causing surges in the pressure of the washing liquid supplied to the nozzle.

The invention is of general utility in the field of washing electrodes of electrical precipitators, but is especially useful in combination with a precipitator of the type disclosed in the co-pending applications of Harry A. Wintermute, Serial No. 576,734, filed February 8, 1945, for Electrical Precipitator (now Patent 2,443,780 dated June 22, 1948), and Serial No. 698,978, filed September 24, 1946, for Electrical Precipitators (now Patent 2,555,216, dated May 29, 1951). Reference may be had to the aforementioned applications for details of the precipitators not disclosed herein.

The principles of the invention will be developed with greater particularity and additional aims and advantages will be in part apparent and in part pointed out in the following detailed

2

description of several embodiments thereof, as shown in the accompanying drawings, wherein:

Fig. 1 is a perspective view of the electrode assembly of an electrical precipitator showing 5 washing liquid conduits and nozzles in assembled position;

Fig. 2 is a side view similar to Fig. 1 showing the washing liquid conduits and nozzles in alternative positions;

10 Fig. 3 is a diagrammatic end view of an electrical precipitator embodying the invention and showing the washing liquid circuit;

Figs. 4 through 6 are enlarged detail views of 15 one form of device for causing surges in the flow of washing liquid to the nozzles;

Fig. 7 is an enlarged sectional view of another 20 form of pressure varying device; and

Fig. 8 is an enlarged view, with parts broken away, of still another form of pressure varying

25 device.

Referring now to the drawings, particularly to Fig. 1 thereof, the electrode assembly shown is of the two-stage type having a charging section 10—10' and a collecting section 11—11'. Gas flows through the apparatus from right to left as seen in Fig. 1. A housing or casing, as indicated at 80 in Fig. 3, is provided to direct the gas stream in the desired path. The charging sections 10 and 10' are in parallel as are also the 30 collecting sections 11 and 11'.

Each precipitator section has an extended surface electrode assembly including a plurality of sheet members 12 rectilinear in the horizontal direction and warped in the vertical direction 35 and positioned in parallel spaced relation to define a plurality of parallel horizontal conduits 13, the sheet members providing extended electrode surface walls to the conduits and providing means guiding the flow of liquids vertically 40 downward from each of said conduits to the subjacent conduit. The sheet members may be conductive, for example, metal sheets or metal surfaced sheet material or they may be non-conductive, when used with conductive liquid films, 45 and they may be perforate or imperforate. They may be shaped to provide conduits of any desired cross-section such as square, as shown, round or hexagonal.

As best seen in Fig. 3, the extended sheet members 50 12 are bent as indicated at 14 to provide liquid receiving troughs 15 at the top of the assembly. The troughs 15 have substantially equal cross-sectional areas so that each trough will receive substantially an equal quantity of liquid 55 descending thereinto in relatively uniform hori-

horizontal distribution from above. Thus, each vertical column of aligned conduits 13 will receive about the same amount of liquid from its communicating trough.

Liquid received in the troughs flows downwardly over the surfaces of the extended surface sheet members 12 through successive subjacent conduits and wets and/or washes the surfaces. Referring to Fig. 1, it will be seen that liquid issuing from the bottom of section 10 falls into the troughs 15 of the lower section 10' and continues in the manner described, to flow down over the extended surfaces of the lower section. Liquid falls from the bottom of section 10' into a sump. It will be understood that the collecting sections 11 and 11' are constructed similarly to the precipitating sections 10 and 10' with regard to the extended surface electrodes, and that the flow of liquid therethrough takes place in a similar manner.

Each of the sections 10, 10', 11 and 11' is provided with high tension electrodes 16, as best seen in Figs. 2 and 3. The electrodes are in the form of rods supported on a frame 17 carried by insulators 18. The rods extend centrally inwardly of the conduits 13 for substantially the entire length thereof. The rods in the charging sections may have fine wire tips to produce corona discharge; those in the collecting sections have no fine wire tips and assist in the establishment of non-discharge fields.

Suitable conduits or cables (not shown) conduct high tension current to the high tension electrodes, as will be understood, and the extended surface electrodes may be grounded or held at some fixed potential.

As regards the operation of the precipitator from the electrical point of view, such operation will be apparent to those skilled in the art. In brief, however, gas bearing suspended particulate matter is passed successively through the charging and collecting sections. With the maintenance of a suitable potential difference between the high tension electrodes and the complementary extended surface electrodes, corona discharge occurs in the charging section 10-10' which charges the suspended particles oppositely to the charge of the extended surface electrodes. In the charging section, some precipitation of the charged particles on the extended surface members 12 occurs, although gas velocities are usually established such that the bulk of the charged suspended particles are transported to the collecting section 11-11'. In the quiescent field of the collecting section, most of the residual charged particulate matter is attracted to and precipitated upon the walls of the extended surface members of that section. Cleaned gas issues from the collecting section.

The extended surface electrodes must be maintained in a clean condition if efficiency is to be preserved. For cleaning or washing the electrodes, distribution of liquid over the surfaces of the extended surface electrodes is accomplished by a device now to be described in detail. In Fig. 1, the pipe 19 is disposed transversely of the flow of gas through the apparatus and centrally above the upper sections 10 and 11. The pipe has a cap 20 closing one end thereof. Along the horizontal median plane of the pipe, a series of spaced orifices 21 are provided in both sides of the pipe walls. These orifices provide nozzles for projecting jets of liquid horizontally and outwardly over the sections 10 and 11. The openings 21 are spaced along pipe 19 corresponding to the

flushing requirements of troughs 15. One orifice may be sufficient for each trough, as shown in Fig. 3. In such case the liquid reaching a top slot 15' as it flows down either or both sides of a trough, divides as it passes through the slot and flows down the surface of each sheet 12 which bounds the tier of conduits immediately below. Where strong flushing is desired the slots 15' are preferably made one-eighth inch or more in width and two orifices 21, spaced apart, are provided for each trough to assure the formation of two substantial films of liquid, each flowing separately down the surface of a sheet 12.

The arrangement of Fig. 2 is similar to that of Fig. 1, differing primarily in the placement of the nozzle pipes. Instead of being centrally located, the nozzle pipes are positioned over the gas inlet and outlet sides of the precipitator and the nozzles are pointed inwardly. The nozzle pipes 19a and 19b supply washing liquid to the upper sections 11 and 10, respectively while the lower nozzle pipes 19c and 19d perform a similar function with respect to the lower sections 11' and 10', respectively. In Fig. 2, the nozzles 21' are tubes as distinguished from simple orifices cut through the side walls of the pipe. The nozzles of each pipe may be arranged to direct their jets into alternate liquid receiving troughs so that the jets from opposite sides do not interfere with each other. Or the jets may be positioned to direct a jet into each trough from each side, in which case, the nozzle-pipes 19a and 19b may be operated out of phase to avoid jet interference.

In Fig. 3, the liquid circuit is shown to best advantage. Liquid is introduced to the precipitator through the nozzle pipes 19-19'. After flowing down through the precipitator sections, the liquid falls into a sump 22 formed in the bottom of the precipitator housing and thence drains through pipe 23 into a settling tank 24 wherein the sludge is allowed to separate. Thickened sludge may be removed as necessary from the tank 24 through a valve controlled pipe 25. Clarified liquid flows through pipe 26 to the rotary centrifugal pump 27 driven by the motor 28 and is circulated through the pipe 29 and the surge controller 30 through pipes 31, 32 and 33 to the nozzle pipes 19 and 19'. Valves 34 and 35, in lines 32 and 33, are provided for eliminating or reducing flow of liquid to either of the nozzle pipes.

The surge controller, indicated generally by the reference numeral 30, may take a variety of forms, three of which will be described herein-after by way of illustration. The purpose of the surge controller is to deliver liquid to the nozzle pipes in a pulsating or surging flow so that liquid jets will be projected some distance from the nozzles during periods of high pressures and at lesser distances therefrom during periods of lower pressures. With oscillating or pulsating delivery of liquid to the nozzles, the jets will oscillate back and forth along the troughs 15, as indicated in Figs. 1 and 2 to distribute liquid more or less uniformly therealong and to insure wetting of the entire longitudinal area of the troughs and the electrode structures thereunder.

One form of surge controller 30' is illustrated in Figs. 4 through 6. This device is actuated by the flow of liquid through it. The controller has a casing 36, rectangular in cross-section, through which liquid flows in the direction of the arrow from the inlet pipe 29 to the outlet pipe 31. An S shaped vane 37, is integrally united to a shaft 38, carried in bearings in the walls of the cas-

ing. The vane has a rectangular profile, as seen in the direction of liquid flow, and, when in the position shown in Figs. 4 and 5, it substantially blocks the flow of liquid through the casing. When the vane is rotated through 90°, the liquid flows freely through the casing. Due to the configuration of the vane, liquid flowing through the casing causes the vane to rotate.

In order to prevent too rapid rotation of the vane and to effect a non-uniform rotation thereof, a cam 39 is fixed to one end of the shaft 38 for rotation therewith. A follower plate 40, pivoted at one end to a pin 41, rides on the cam surface and is yieldingly pressed into contact therewith by a spring 42, tensioned between the other end of the follower plate and a base 43. The cam-and-follower arrangement effectively controls the period of surge imparted to the liquid flowing to the nozzle pipes 19 to give the desired jet action.

The surge controller 38' shown in Fig. 7 also is operated by flow of liquid therethrough; it includes the inlet and outlet pipes 29 and 31 and a cylinder 44 having an inlet chamber 45 and an outlet chamber 46 separated by a sliding piston 47 having a port 48 in the piston face and another port 48' in the skirt. The piston is yieldingly urged toward the inlet chamber by a compression spring 49. The inlet pipe 29 is connected by a by-pass pipe 50 to the outlet chamber 46 through a port 51 which is closed by the piston skirt where the piston is moved to the right and is opened by movement of the piston in the opposite direction to bring the ports 48' and 51 into registry.

The controller of Fig. 7 operates automatically. As liquid is forced through the pipe 29, it enters the inlet chamber 45 and moves the piston 47 to the left against the force of spring 49 to bring the ports 48' and 51 into registry. Liquid then flows through the by-pass pipe 50 into the chamber 46 and by way of the pipe 31 to the nozzle pipes. Back pressure induced by the nozzles increases the pressure in the outlet chamber 46 to a value approaching the value of the pressure in the inlet chamber 45, the port 48 assisting to equalize pressures in the two chambers. A point is reached where the force of the spring 49 is sufficient to move the piston to the right against the differential force existing across the piston head. Such movement closes the by-pass port 51 and reduces the flow of liquid through the controller to that which passes through the port 48. The pressure in the chamber 46 soon falls to a value such that the pressure differential between chambers 45 and 46 creates a force sufficient to move the piston 47 to the left to start a new cycle. The cyclic movement of the piston effects a surging of pressure at the delivery nozzles to cause the area of impingement of the jets issuing from the nozzles to oscillate along the tops of the electrodes.

In Fig. 8, there is shown a positive action, externally actuated gate valve 30''' for controlling the surges of liquid delivered to the nozzle pipes. The valve has the usual gate 52 vertically slidable in the guides 53 to open and close the valve. The gate 52 has a rod 54 extending upwardly to an external cross-head 55 having a horizontal slot 56 in which is received the pin 57, eccentrically mounted on the wheel 58 rotated by the shaft 59. The pin-and-wheel construction constitutes a crank which, when rotated, moves the cross-head, rod and valve gate up and down to open and close the valve or to change the valve

opening in accordance with a predetermined cycle. Operating in this manner, the valve may be used to control surges in the liquid delivered to the nozzle pipes.

In view of the foregoing, other surge controlling devices will occur to those skilled in the art. Such devices may be used advantageously with rotary pumps or the like or with other means supplying liquid under more or less constant pressure. A surging flow of liquid may, however, be delivered to the nozzle devices by a single cylinder single action pump which, by its nature, delivers a surging flow of liquid.

For purposes of illustration, the washing device has been described in connection with one particular form of electrical precipitator. It will be understood that the invention has broader application in the field of electrical precipitation and may be successfully used for washing or wetting the extended surface electrodes of other types of precipitators, such as those wherein the extended surface electrodes are in the form of flat plates. In general, where sprays or solid jets of liquid are directed against electrodes, the present invention may be employed advantageously with the elimination of a large number of the spray heads previously used.

As employed herein, the terms "nozzle" and "jet" have their broad meanings. A "nozzle" may be a simple orifice or a complicated spray head. A "jet" may be a more or less solid stream of liquid or a somewhat diffuse spray. The term "washing" is also used in a broad sense to include the wetting of electrode structures wherein the volume of liquid used is insufficient to wash the electrodes but is sufficient to supply a uniform film of liquid thereto, as for the purpose of treating the gas flowing through the precipitator or modifying the conductive characteristics of the electrodes.

I claim:

1. In an electrical precipitator including substantially vertically disposed spaced parallel extended surface electrodes and complementary high tension electrodes, each of said extended surface electrodes having an upper portion inclined to the vertical to provide a sloping surface extending along substantially the entire top edge of the extended surface electrode and a dependent extended surface portion continuous with said inclined upper portion, stationary nozzle means positioned to play a jet of washing liquid back and forth on the inclined upper portion of said electrode along a line extending substantially parallel to the top edge of the dependent extended surface portion of said electrode as the pressure of washing liquid in the nozzle is varied between predetermined limits, means including a conduit supplying washing liquid to said nozzle, and means for cyclically varying the pressure of the liquid in the nozzle between said predetermined limits.

2. In an electrical precipitator including substantially vertically disposed spaced parallel extended surface electrodes rectilinear in the horizontal direction and complementary high tension electrodes, each of said extended surface electrodes having an upper portion inclined to the vertical to provide a sloping surface extending along substantially the entire top edge of the extended surface electrode and a dependent extended surface portion continuous with said inclined upper portion, stationary nozzle means positioned to play a jet of washing liquid back and forth on the inclined upper portion of said

electrode along a line extending substantially parallel to the top edge of the dependent extended surface portion of said electrode as the pressure of washing liquid in the nozzle is varied between predetermined limits, means including a conduit supplying washing liquid to said nozzle, and means for cyclically varying the pressure of the liquid in the nozzle between said predetermined limits.

3. Apparatus as defined in claim 2 wherein the dependent extended surface portions of said electrodes are warped in the vertical direction to define a plurality of horizontal flues.

4. Apparatus as defined in claim 2 wherein said washing liquid supplying means comprises a source of liquid under substantially constant pressure.

5. Apparatus as defined in claim 2 wherein said washing liquid supplying means comprises a centrifugal pump.

6. Apparatus as defined in claim 2 wherein said washing liquid supplying means comprises a centrifugal pump and said pressure varying means comprises means positioned in said conduit between said pump and said nozzle means and actuated by movement of liquid therethrough.

7. Apparatus as defined in claim 2 wherein said washing liquid supplying means comprises a centrifugal pump and said pressure varying means comprises an independently operated valve positioned in said conduit means between said pump and said nozzle means.

8. In an electrical precipitator including substantially vertically disposed spaced parallel extended surface electrodes rectilinear in the horizontal direction and complementary high tension electrodes, each of said extended surface electrodes having an upper portion inclined to the vertical to provide a sloping surface extending along substantially the entire top edge of the extended surface electrode and a dependent extended surface portion continuous with said inclined upper portion, stationary nozzle means positioned to play a jet of washing liquid back and forth on the inclined upper portion of said electrode along a line extending substantially

parallel to the top edge of the dependent extended surface portion of said electrode as the pressure of washing liquid in the nozzle is varied between predetermined limits, means including a conduit supplying washing liquid to said nozzle, and means in said conduit means actuated by movement of liquid therethrough for cyclically varying the pressure of the liquid in the nozzle between said predetermined limits.

10 9. In an electrical precipitator including substantially vertically disposed spaced parallel extended surface electrodes rectilinear in the horizontal direction and complementary high tension electrodes, each of said extended surface electrodes having an upper portion inclined to the vertical to provide a sloping surface extending along substantially the entire top edge of the extended surface electrode and a dependent extended surface portion continuous with said inclined upper portion, stationary nozzle means positioned to play a jet of washing liquid back and forth on the inclined upper portion of said electrode along a line extending substantially parallel to the top edge of the dependent extended surface portion of said electrode as the pressure of washing liquid in the nozzle is varied between predetermined limits, means including a conduit supplying washing liquid to said nozzle, and means including an independently operated valve in said conduit means for cyclically varying the pressure of the liquid in the nozzle between said predetermined limits.

35 JOHN HERBERT WILSON.
